UNITED STATES PATENT OFFICE

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE

TYPEWRITING MACHINE

Application filed October 20, 1928. Serial No. 313,686.

This invention relates to typewriting machines, which are provided with tabulating mechanism serviceable for billing work. Such mechanism includes, as in the standard Underwood machine, a row of decimal and other tabulating keys arranged in front of the machine-frame, each key depressible to jump the carriage for certain columns according to its denomination.

More particularly the invention contemplates an auxiliary mechanism or attachment for facilitating the operation of said tabulating keys. These attachments are useful where special billing work requires frequent use of a certain tabulating key, and are known to preferably include a palm-key, which, through a train of members, may be operatively connected and selectively adjusted to any one of said tabulating keys. To locate and manipulate a certain handy palm-key instead of one of the small decimal-keys is convenient, and therefore time and labor saving, while also precluding possible faulty tabulation on the part of the operator.

The object of the invention is to provide an improved attachment which is durable, compact, simple, and easily accessible for mounting and adjusting the same, a mechanism of more effective action and which may be attached to standard machines without constructive change thereof.

A mechanism of the preferred class, as heretofore proposed and shown in the patent to Kurowski No. 1,668,915, will not meet the requirements, especially of easy mounting and accessibility, the mechanism being hidden away within the machine-frame and crowded in between two superposed layers or rows of key-levers. It may be mounted and set for a certain establishment, from the bottom only after lifting up the whole of the machine, or even turning the same up-side down.

Such practice becomes particularly objectionable when, as is the case in a particular embodiment of the invention, the Underwood typewriting machine is, in a well-known manner, permanently combined with a computing machine which forms the lower bulky part or base of an arrangement known

as a bookkeeping machine. Under such conditions the mechanism in said patent could not be mounted or adjusted without dismounting the whole machine from its base and eventually requiring the assistance of an expert mechanic, and moreover is liable to interfere with the structure of the computing machine.

To overcome these difficulties, a feature of the invention provides actuating mechanism, which, in the form of a compact unit, may be mounted upon the machine-frame structure in a manner to be freely accessible.

Another feature provides means for manipulating a key-selector from the outside when adjusting the same to a selected tabulating key.

Constructive features of the novel design will disclose the advantages as mentioned above: Supporting structure extends forwardly from the front of the machine to carry a rock-shaft which extends across the machine underneath and adjacent the front ends of the tabulating key-levers. Settable means upon said shaft, which enable the mechanism to be selectively connected to any one of the tabulating keys, are now freely accessible from the front. They may include a crank-arm ranging backwardly toward the key-levers, and a hook-member to engage over the front portion of a tabulating key-lever. To aid in adjusting the crank-arm there may be provided a milled face extending from end to end of the shaft, along which the crank-arm is slidable and upon which it may be suitably fastened.

When operating the device the shaft is rocked against spring-pressure, a spring being coiled around the rock-shaft, and thus forming part of the unit. An amply-sized palm-piece is also included in the unit at a place convenient to the operator, and has a stem to be slidable up and down, whereby the up-and-down movement is rigidly limited within the unit to securely take up a violent blow of the palm and without injurious effect to the tabulating mechanism proper. A more effective cam-roller connection transmits movement from the palm-piece to the rock-shaft to operate the latter when tabulating.

It will thus be seen that the construction is compact, durable and accessible. The space available in front of the machine allows highly stressed parts to be built as strong as practicable, while operating leverages are kept reasonably small, thus minimizing the danger of deformation of parts, the general operation of the machine in no way being interfered with. The construction further-
more is cheap and simple, comprising parts made from flat or other stock-material.

Other features and advantages will hereinafter appear.

In the accompanying drawings,

Figure 1 is a perspective view, showing a row of decimal-tabulating keys in relation to adjacent parts of a combined typewriting and computing machine and the improved key-actuating mechanism, mounted thereon in inoperative position.

Figure 2 is an operative view taken from Figure 1, and indicating a palm-piece as being depressed to actuate a certain selected tabulating key.

Figure 3 is a detail view, showing a convenient method of connecting and disconnecting a tabulating key to and from the novel key-actuating mechanism.

The preferred embodiment of the invention applies to an Underwood bookkeeping machine which includes a standard typewriter indicated by the front part of its frame 10, by standard space-bar 11 and keys 12 (dot and dash), and furthermore includes a well-known computing machine. The typewriting machine is mounted upon the computing machine, which latter is actuated by the depressions of the numeral-keys of the typewriter. The external structure or housing 13 of the computing machine forms the base of the typewriting machine and has lateral portions 14 embracing the lower part of the typewriter-frame. The front part of said housing is represented by a cover or shield-plate 15 fastened by screws 16 upon said housing 13, and opening 17 in the cover being shown to expose one of the usual computing heads or registers of the machine, (not shown.) A well-known tabulating mechanism provided in the typewriting machine is indicated only by a row of tabulating key-buttons 18 which form the terminals of key-levers 18^a extending from underneath the machine-frame forwardly into the reach of the operator. Said shield-plate 15 gives an opportunity to guide the tabulating key-levers in their downward movement by slots 19, and takes the place of a special combination ordinarily used on typewriters with tabulating mechanism. It furthermore permits an improved key-actuating mechanism to be conveniently mounted thereon. This novel mechanism includes a compressible palm-piece 20 and is operatively connectible to any of the tabulating keys, whichever may be se-

lected, for purposes of convenience, as described above.

The mechanism includes a rock-shaft 21 journaled at one end in a plain bracket 22 and at the other end in a special bracket 23, both brackets secured upon the shield-plate 15. Constructively, the special bracket 23, at the left-hand side of the machine, represents particular features. It is integrally made out of flat material and is formed with a body-portion 24 fastened by screws 25 upon the shield-plate 15. From the body-portion 24 extend forwardly two bent-over bearing-
portions 26 to receive therein the rock-shaft 21, and forming a U-shaped bearing-structure which is apt to embrace rocking elements including a crank-arm 27 mounted upon the rock-shaft and carrying a cam-roller 28, and to house a spring 29 coiled around the rock-shaft and normally effective to urge the rock-shaft to inoperative position while tensioned between the bracket 23 and the crank-arm 27. The body portion of the bracket 23 has an upward extension 30 formed with lateral bent-over guiding portions 31 to receive vertically slidably therein a stem 32 upon which is rigidly fastened, as by rivets 33, said palm-piece 20. The lower end of the stem is formed with an angular portion 34 to present a cam-face co-operative with said cam-roller 28. The up-and-down operating movement of the palm-piece may be determined by a screw-and-slot connection, as provided at 34^a, between the stem 32 and bracket 23 respectively. Depression of the palm-piece, when violently exerted, will then be securely taken up without detrimentally affecting the tabulating mechanism, while the blow is to be intercepted by the rigid machine-frame. Operation of the palm-piece will rock the shaft against spring-tension and will cause a crank-arm 35 to actuate a selected tabulating key, for instance 36, to which it may be connected by means of a hook 37. The crank-arm 35 extends rearwardly from the shaft and carries at its free end, pivoted thereon by a shoulder-screw 35^a, said hook 37. The crank-arm 35 is laterally settable along the shaft so as to be selectively connectible to any of the tabulating keys, at which point it should be noted that the rock-shaft is provided from end to end with a milled face 37^a, which allows the crank-arm 35 to be slidable thereon, besides offering other advantages, for the crank-arm is cheaply made from flat material and formed with a bent-over ear 38 which flatly engages upon said milled face to stabilize the crank-arm in its various shift positions, to aid in adjustment. A fixing screw 39 may be passed through said ear 38 and conveniently threaded into the rock-shaft to fix the crank-arm in place. A series of threaded holes 40 may be easily provided in said milled face, spaced in harmony with the tabulating keys, for fixing the actuating crank-arm 35 at pre- 133

terminated places, and so that the fixing screw 39 may be easily accessible from the front.

Figure 3 is to illustrate the method of attaching the crank-arm to a tabulating key, whereby the fixing screw is first loosened and then the associated tabulating key depressed to release the hook 37 from the key-lever 18. The crank-arm, now being free for lateral movement, may be slid for connection to another tabulating key, where the hook is to be attached in the same manner and the crank-arm secured in place by simply placing the screw in the established threaded hole. The first-mentioned crank-arm 27, which carries the cam-roller 28, is fastened upon the rock-shaft in the same simple and effective manner. To prevent the rock-shaft from undue lateral displacement, there are provided collars 41, which may be easily fixed in position by means of set-screws 42 engaging upon the established milled face 37^a upon the rock-shaft.

At 43 and 44, respectively, are shown the so-called "subtraction-key" and the "credit-balance key" which are found on standard computing machines, and shown, for instance, in Patent No. 1,452,162 to Kupetz. It is clear that the novel key-actuating mechanism does not interfere with the operation of these standard computing keys.

From the above, it is readily seen that the improved mechanism forms a desirable manufacturing unit which may be conveniently attached to standard machines and set from the outside.

Variations may be resorted to within the scope of the invention, and portions of the improvements may be used without others.

Having thus described my invention, I claim:

1. In a typewriting machine having decimal tabulating mechanism, the combination with a row of depressible tabulating keys adjacent the front of the machine-frame, including key-levers, of an auxiliary mechanism for selectively actuating one of the tabulating keys when its continued use for special work is required, said auxiliary mechanism including a rock-shaft extending transversely of the machine, outside of the machine-frame, and adjacent the front ends of said tabulating key-levers, means for supporting the shaft upon the machine-frame, means including a palm-piece for rocking the shaft, and means laterally settable upon said shaft and effective to actuate a selected tabulating key when the shaft is rocked, said settable means being supported in a manner to be manipulated from the outside.

2. In a typewriting machine having decimal tabulating mechanism, the combination with a row of tabulating keys arranged in front of the machine-frame, of an auxiliary mechanism operable for selectively actuating one of the tabulating keys when its continued

use for special work is required, said auxiliary mechanism including a rock-shaft extending transversely of the machine, adjacent the tabulating keys, supporting structure extending forwardly from the front of the machine-frame for supporting the shaft, means including a palm-piece for rocking the shaft, and means laterally settable upon said shaft, and ranging backwardly, towards the keys, and effective to actuate a selected tabulating key when said shaft is rocked, said settable means manipulated from the front.

3. In a typewriting machine having decimal tabulating mechanism, the combination with a row of tabulating keys at the front of the machine-frame, of an auxiliary mechanism operable for actuating a certain selected tabulating key when its continued use for special work is required, said auxiliary mechanism including a rock-shaft having a flat face, extending from end to end thereof, said shaft extending transversely of the machine, adjacent the tabulating keys, means for supporting said shaft upon the machine, means including a palm-piece for rocking the shaft, means settable upon said shaft, to be operatively connected to a selected tabulating key, and including a crank-arm of flat material having a bent-over ear to engage upon said flat face, to be slidable thereon, so as to aid in adjustment of the settable parts, and means for securing said crank-arm in adjusted position.

4. In a typewriting machine having decimal tabulating mechanism, the combination with a row of tabulating keys at the front of the machine-frame, of an auxiliary mechanism operable for actuating a certain selected tabulating key when its continued use for special work is required, said auxiliary mechanism including a rock-shaft having a flat face, extending from end to end thereof, said shaft extending transversely of the machine, adjacent the tabulating keys, means for supporting said shaft upon the machine, means including a palm-piece for rocking the shaft, means settable upon said shaft, to be operatively connected to a selected tabulating key, and including a crank-arm of flat material having a bent-over ear to engage upon said flat face, to be slidable thereon, so as to aid in adjustment of the settable parts, and screw-means to secure said bent-over ear upon said shaft when the crank-arm is in adjusted position, said screw-means to be accessible from the front.

5. In a typewriting machine having decimal tabulating mechanism, the combination with a row of tabulating keys at the front of the machine-frame, of an auxiliary mechanism operable for actuating a certain selected tabulating key when its continued use for special work is required, said auxiliary mechanism including a rock-shaft adjacent

the tabulating keys, means for supporting the shaft upon the machine, means upon said shaft for selectively actuating the tabulating keys when rocking the shaft, means including a palm-piece for rocking the shaft, a stem to support said palm-piece, means for positively guiding said stem in up and down movement, and a rigid stop-means to limit said movement when the palm depresses said palm-piece against spring pressure.

6. In a typewriting machine having decimal tabulating mechanism, the combination with a row of tabulating keys at the front of the machine-frame, of an auxiliary mechanism operable for actuating a certain selected tabulating key when its continued use for special work is required, said auxiliary mechanism including a rock-shaft adjacent the tabulating keys, means for supporting the shaft upon the machine, means upon said shaft for selectively actuating the tabulating keys when rocking the shaft, means including a palm-piece for rocking the shaft, a stem to support said palm-piece, means for positively guiding said stem in up and down movement, rigid stop-means to limit said movement when the palm depresses said palm-piece against spring pressure, and cam-mechanism to transmit movement from the palm-piece to the rock-shaft, including a cam-face portion upon the lower end of said stem and co-operative cam-means provided upon one end of said rock-shaft.

7. In a typewriting machine having decimal tabulating mechanism, the combination with a row of tabulating keys at the front of the machine-frame, of an auxiliary mechanism operable for actuating a certain selected tabulating key when its continued use for special work is required, said auxiliary mechanism including a rock-shaft adjacent the tabulating keys, means upon said shaft for selectively actuating the tabulating keys when rocking the shaft, means including a palm-piece for rocking the shaft, a stem of flat material to support said palm-piece, means for positively guiding said stem in up and down movement, rigid stop-means to limit said movement when the palm depresses said palm-piece against spring pressure, cam-means on one end of said shaft, and a bent-over portion at the lower end of said stem, presenting a cam-face to co-operate with said cam-means.

8. In a typewriting machine having decimal tabulating mechanism, the combination with a row of tabulating keys at the front of the machine-frame, of an auxiliary mechanism operable for actuating a certain selected tabulating key when its continued use for special work is required, said auxiliary mechanism including a rock-shaft adjacent the tabulating keys, means upon said shaft for selectively actuating the tabulating keys when rocking the shaft, means including a palm-piece for rocking the shaft, a stem to support said palm-piece, means for positively guiding said stem in up and down movement, rigid stop-means to limit said movement when the palm depresses said palm-piece against spring pressure, and cam-means between said palm-piece and said shaft, a cam-arm being provided at one end of the shaft, a U-shaped bracket to support one end of the shaft, and arranged to embrace said cam-means for sake of compactness.

ing a palm-piece for rocking the shaft, a stem to support said palm-piece, a bracket mounted upon the machine, upon which to positively guide said stem in up and down movement, stop-means to rigidly limit said movement upon said bracket when the palm depresses the palm-piece against spring pressure, and cam-means between the lower end of said stem and the rock-shaft to rock the latter while operating the palm-piece.

9. In a typewriting machine having a decimal tabulating mechanism, the combination with a row of tabulating keys at the front of the machine-frame, of an auxiliary mechanism operable to actuating a certain selected tabulating key when its continued use for special work is required, said auxiliary mechanism including a rock-shaft adjacent the tabulating keys, means upon said shaft for selectively actuating the tabulating keys when rocking the shaft, means for rocking said shaft, including a palm-piece and cam-means between said palm-piece and said shaft, a cam-arm being provided at one end of the shaft, and a U-shaped bracket to support one end of the shaft, and arranged to embrace said cam-means for sake of compactness.

10. In a typewriting machine having decimal tabulating mechanism, the combination with a row of tabulating keys at the front of the machine-frame, of an auxiliary mechanism operable for actuating a certain selected tabulating key when its continued use for special work is required, said auxiliary mechanism including a rock-shaft adjacent the tabulating keys, means upon said shaft for selectively actuating the tabulating keys when rocking the shaft, means for rocking said shaft, including a palm-piece and cam-means between said palm-piece and said shaft, a cam-arm being provided at one end of the shaft, a U-shaped bracket to support one end of the shaft, and arranged to embrace said cam-means for sake of compactness, and spring-means also embraced by said U-shaped bracket and effective to return the rock-shaft to inoperative position after the palm-piece has been depressed.

11. In a typewriting machine having decimal tabulating mechanism, the combination with a row of tabulating keys at the front of the machine-frame, of an auxiliary mechanism operable for actuating a certain selected tabulating key when its continued use for special work is required, said auxiliary mechanism including a rock-shaft adjacent the tabulating keys, means upon said shaft for selectively actuating the tabulating keys when rocking the shaft, means for rocking said shaft, including a palm-piece and cam-means between said palm-piece and said shaft, a cam-arm being provided at one end of the shaft, a U-shaped bracket to support one end of the shaft, and arranged to embrace said cam-means for sake of compactness, and spring-means also embraced by said U-shaped bracket and effective to return the rock-shaft to inoperative position after the palm-piece has been depressed.

brace said cam-means for sake of compactness, and a torsion spring coiled around one end of said shaft, to be embraced by said U-shaped bracket, and engaging upon said 5 cam-arm, tending to return the rock-shaft to inoperative position after the palm-piece has been depressed.

of said tabulator-keys, and a spring for returning said rock-shaft; said rock-shaft having threaded holes at intervals corresponding to the spacing of said tabulator-keys, and said arm provided with a screw which can be 70 threaded into any of said holes.

ALFRED G. F. KUROWSKI.

12. In a typewriting machine having decimal tabulating mechanism, the combination 10 with a row of tabulating keys at the front of the machine-frame, of an auxiliary mechanism operable for actuating a certain selected tabulating key when its continued use for special work is required, said auxiliary mechanism 15 including a rock-shaft adjacent the tabulating keys, means upon said shaft for selectively actuating the tabulating keys when rocking said shaft, means for rocking said shaft, including a palm-piece and cam- 20 means between said palm-piece and said shaft, there being provided a cam-arm at one end of the shaft, and a U-shaped bracket to support the shaft at one end thereof, and arranged to embrace said cam-arm, said U- 25 shaped bracket having an upward extension to receive thereon the depressible palm-piece, said palm-piece having a vertically-slidable stem, said stem effective to engage upon said cam-arm, to rock the shaft when the palm- 30 piece is operated.

13. In a typewriting machine having a framing enclosing a keyboard, and also having decimal tabulator-keys in front of the keyboard, the combination of a bracket-device 35 detachably secured to the machine-framing and including a vertical guide, a stem movable up and down in said vertical guide, a palm-key surmounting said stem and overhanging the typewriter-framing at the front 40 of the keyboard, a cam-face upon said stem, a rock-shaft extending along the keyboard and mounted in said bracket-device, a depressible cam-means upon said rock-shaft to be engaged by said cam-face, an arm adjustable 45 along said rock-shaft to position to co-operate selectively with different tabulator-keys, and means to connect said arm releasably to any of said tabulator-keys.

14. In a typewriter machine having a 50 framing enclosing a keyboard, and also having decimal tabulator-keys in front of the keyboard, the combination of a bracket-device detachably secured to the machine-framing and including a vertical guide, a stem 55 movable up and down in said vertical guide, a palm-key surmounting said stem and overhanging the typewriter-framing at the front of the keyboard, a cam-face upon said stem, a rock-shaft extending along the keyboard 60 and mounted in said bracket-device, a depressible cam-means upon said rock-shaft to be engaged by said cam-face, an arm adjustable along said rock-shaft to position to co-operate selectively with different tabulator-keys, 65 means to connect said arm releasably to any
